UNITED STATES PATENT OFFICE.

LOUIS MYERS, OF DETROIT, MICHIGAN, ASSIGNOR TO MACHINE APPLIANCE CORPORATION, OF BROOKLYN, NEW YORK, A CORPORATION OF NEW YORK.

FASTENER-FEEDING MECHANISM.

1,255,551.

Specification of Letters Patent. Patented Feb. 5, 1918.

Application filed April 21, 1917. Serial No. 163,544.

To all whom it may concern:

Be it known that I, LOUIS MYERS, a citizen of the United States, residing at Detroit, Michigan, have invented certain new and 5 useful Improvements in Fastener-Feeding Mechanism, of which the following is a full, clear, and exact description.

My invention relates to fastener feeding mechanism and has for its object to produce 10 a mechanism for feeding fasteners to a magazine in a machine for inserting and securing said fasteners through material to be fastened. It is particularly applicable to eyeleting machines, and has for its object to 15 feed the fasteners, one at a time, into the magazine in such a manner that the liability of the mechanism to become blocked in such a manner as to injure the fasteners is avoided.

20 It further has for its object to provide a mechanism which is not liable to be injured by the blocking of the same by a fastener, or the return movement of the handle.

25 It further has for its object to provide a feeding mechanism, having a reservoir which is oscillated during the operation of the machine.

30 It further has for its object to provide a new and improved reservoir. My invention constitutes an improvement upon the eyeletting machine shown and described in my Patent No. 1,174,948, granted March 7, 1916.

35 The following is a description of an embodiment of my invention, reference being had to the accompanying drawings, in which:

Figure 1 is a side elevation of a machine embodying my invention;

40 Fig. 2 is a section of the upper portion of the same;

Fig. 3 is a side elevation of the reservoir, showing a portion of its supporting and actuating means;

45 Fig. 4 is a bottom plan view of the same with the portion of its containing cup and stud removed;

Fig. 5 is a detail view of the handle gear;

50 Fig. 6 is a bottom plan view of the gear, looking in the direction of the arrow, Fig. 2, and showing the handle and punch in dotted lines;

Fig. 7 is a detail view of one of the friction washers.

55 Referring more particularly to the drawings, which show my invention embodied in

an eyeleting machine, 1 is the base of an eyeleting machine to which are riveted side plates 1¹ and 1²; 2 is a punch for receiving the eyelets and forcing them through the material to be fastened. The punch is 60 guided by plates 2' 2² supported by the side plates; 3 is an anvil, co-acting with the punch; 4 is a plunger, protruding from the lower end of the punch and movable upward therein, being held in projected position by 65 a spring 5. 6 is a spring which normally holds the punch in elevated position; 7 is a handle having a cam 8 which acts upon the upper end of the punch to force the punch downward when the handle is depressed; 9-70 is a magazine feeding eyelets to springs 10, which support the eyelets beneath the plunger, so that when the punch is brought down the plunger passes through them and carries them toward the anvil. Above the upper end of the magazine is a reservoir 11 formed of an inverted cup 12 and base-plate 13. Said cup is provided with a series of 75 projections 14, forming spaces 15, through which the eyelets can pass one at a time. 80 These projections terminate in pins 16 which pass through holes provided in the base-plate 13, being then turned over so as to hold the base-plate to the cup. Mounted on the frame of the machine is a cup 17 having a bearing 17' supporting a rotatable stud 18, having on its lower end a gear wheel 19 and on its central portion two washers 20, one on each side of the base plate 13. The cup has on its edge adjacent to the magazine 85 an opening so shaped as to allow the passage of fasteners from the reservoir into the magazine. Above the base-plate and upper washer 20, and upon said stud 18, is a compression spring 21, and above this spring is 90 a nut 22 for holding the spring 21. The washers 20 are friction washers, having flats 22 which engage a flat 23 upon the stud, so that they are prevented from turning relatively thereto. The base of the reservoir is 95 thus held by a frictional grip between these two washers, which produce a friction thereon, tending to cause the reservoir to follow every movement of the stud, but permitting the stud to turn independently of the reservoir in case the reservoir should become 100 wedged.

105 Mounted adjacent to the handle is a gear member 24 having gear teeth engaging the small gear 19 and having a flat edge 25 110

which engages an abutment 26 upon the handle. A pivot pin 27 passes through the handle and gear member 24 into the sides 1—1' of the machine and holds these parts 5 in assembled position.

The cup 17 is held to the side plates by headed projections 28. The handle on its return stroke is prevented from hitting the cup 17 by a pin 29 passing through the side 10 plates.

The operation of the device is as follows:

Assuming that the reservoir is free to revolve, the downward movement of the handle causes the gear member 24 to revolve, 15 and this engaging the small gear 19, causes it and its stud to revolve, and the reservoir is carried around thereby on account of the friction of the two washers. An upward movement of the handle results in a reverse 20 movement of the reservoir. It sometimes happens, however, that a fastener will wedge between one of the projections at the bottom of the reservoir and the opening in the cup. This will stop the reservoir, and the friction 25 connection with the stud permits such stoppage without injury. Upon the reverse movement of the handle, however, the movement of the reservoir in the opposite direction moves the fastener so that it is freed and 30 either moves around with the reservoir or falls into the magazine so as to be fed to the punch. On account of the friction connection, the wedging above referred to does not result in injuring either the reservoir, the 35 cup, the magazine or the fastener, and the machine automatically becomes unblocked. The handle is returned by the spring 6 and prevented from hitting the cup 17 by the pin 29.

40 As will be evident to those skilled in the art, my invention permits of various modifications without departing from the spirit thereof or the scope of the appended claims.

What I claim is:

45 1. In a mechanism for feeding fasteners, the combination of a cup having a bearing for a stud; a stud mounted therein; a reservoir through the bottom of which the upper end of said stud passes; a washer upon said stud below said reservoir and fixed against axial movement relative to said stud; means for holding the bottom of said reservoir against said washer, so as to produce a driving 50 friction, and means for moving said stud about its axis.

2. In a mechanism for feeding fasteners, the combination of a cup having a bearing for a stud; a stud mounted therein and having gear teeth on its lower end; a reservoir 55 through the bottom of which the upper end

of said stud passes; a washer upon said stud below said reservoir fixed against axial movement relative to said stud, and means for holding the bottom of said reservoir against said washer, said means consisting 65 of a spring and a holding device upon the upper end of said stud; and a pivotally mounted handle having gear teeth driven thereby meshing with the gear teeth on said stud.

3. In a mechanism for feeding fasteners, the combination of a cup having a bearing for a stud; a stud mounted therein having gear teeth on its lower end; a reservoir through the bottom of which said stud 75 passes; a washer upon said stud, in engagement with said reservoir bottom and fixed against axial movement relative to said stud; means for holding the bottom of said reservoir against said washer; a handle pivotally mounted in said frame and a gear member carried thereby meshing with the gear teeth on said stud, said handle and gear member having engaging abutments, so as to prevent their relative rotation, and a 80 bearing pin passing through said handle and gear member.

4. In a fastener machine, the combination of a cup having a bearing for a stud; a stud carried thereby; means for rotating said 90 stud; a base plate mounted on said stud so as to be frictionally driven thereby, said base plate having around its periphery a series of perforations and an inverted cup having downward projections, providing openings 95 for the passage of fasteners, and extensions from said projections passing through the holes in the base plate and secured therein.

5. In a mechanism for feeding fasteners, the combination of a cup having a bearing 100 for a stud; a stud mounted therein; a reservoir frictionally driven by said stud; frame members to which said cup is secured; a handle pivotally mounted in said frame; means for oscillating said stud as said handle is oscillated; a spring for returning said handle to normal upper position, and a stop carried by said frame for limiting the upward movement of said handle.

6. In mechanism for feeding fasteners, the 110 combination of a cup having a bearing for a stud, a magazine leading from said cup, a stud mounted in said bearing, a reservoir movable relatively to said stud and through the bottom of which said stud passes, means 115 for reciprocating said stud, and means for holding said reservoir on said stud so that said reservoir tends to follow the reciprocating movements of said stud.

LOUIS MYERS.
